HINGE LEAF

Raymond U. H. Tegner, Rockford, Ill., assignor to Amerock Corporation, Rockford, Ill., a corporation of Connecticut

Filed May 26, 1969, Ser. No. 17,350

Term of patent 14 years

Int. Cl. D8—03

U.S. Cl. D8—195

FIG. 1 is a front view of a hinge leaf incorporating my new design.

FIG. 2 is a side view as seen from the left in FIG. 1.

FIG. 3 is an enlarged top view of a hinge leaf.

FIG. 4 is an enlarged sectional view taken along the line 4—4 in FIG. 2.

FIG. 5 is an enlarged sectional view taken along the line 5—5 in FIG. 1.

FIG. 6 is an enlarged fragmentary sectional view taken along the line 6—6 in FIG. 1.

The broken lines are for illustrative purposes only.
I claim:

The ornamental design for a hinge leaf, as shown and described.
